DESIGN FOR AN ELECTRIC IRON

Donald L. Hadley, Mansfield, Ohio, assignor to
Westinghouse Electric & Manufacturing Com-
pany, a corporation of Pennsylvania

Application May 11, 1934, Serial No. 51,745

Term of patent 7 years

To all whom it may concern:

Be it known that I, DONALD L. HADLEY, a citizen of the United States, residing at Mansfield, in the county of Richland and State of Ohio, have invented a new, original, and ornamental Design for Electric Iron, of which the following is a specification, reference being had to the accompanying drawing, constituting a part hereof:

Figure 1 is a view in side elevation of an electric iron showing my new design.

Fig. 2 is a top plan view thereof.
Fig. 3 is a view, in rear elevation thereof, and
Fig. 4 is a sectional view through the handle
taken on the line IV—IV of Fig. 2.

I claim:

The ornamental design for an electric iron substantially as shown.

In testimony whereof, I have hereunto sub-
scribed my name this 9th day of May, 1934.

DONALD L. HADLEY.
